UNITED STATES PATENT OFFICE.

THOMAS G. FROTHINGHAM, OF BOSTON, MASSACHUSETTS.

SHOT.

1,249,372.

Specification of Letters Patent. Patented Dec. 11, 1917.

Application filed September 26, 1916. Serial No. 121,117.

To all whom it may concern:

Be it known that I, THOMAS G. FROTHINGHAM, a citizen of the United States, and a resident of Boston, in the county of Suffolk and State of Massachusetts, have invented certain new and useful Improvements in Shots, of which the following is a specification.

My invention relates to a new and useful improvement in shots, especially chain shots now obsolete in warfare owing to the non-adaptability of such chain shots of known construction to modern gunnery, where accuracy and range are essential.

10 The object of my invention is to produce an improved shot of the chain shot type which will overcome the present difficulty of securing an effective hit on an air craft or other object which it is sought to injure or 15 destroy, as shrapnel or such other missiles, either shoot too far or too short before scattering, and the effect thereof is lost on the object aimed at. The injury or damage from a shot constructed according to my invention will be possible over long distance 20 of the shot's travel, as it will make a large hole in the object aimed at anywhere in its course, owing to its spread and tearing effect during its flight through the air.

25 These and other objects are accomplished by the device hereinafter described and particularly set forth in the claims.

In the accompanying drawing which illustrates my invention:

30 Figure 1 is a detail view of the improved chain shot.

Fig. 2 is an elevation of the shot assembled and ready to put in the gun.

35 Fig. 3 is a detail view partly in section showing the chain shot assembled in a cartridge case in position for firing.

Like letters of reference refer to like parts throughout the several views.

The shot A consists of two sections B and 40 C respectively provided with inner recesses B' and C' in which recesses the chain D secured at B' and C' to the sections B and C respectively is coiled when the assembled shot is placed in the gun, thus giving a true bearing of one section of the shot upon the other.

45 As shown in Fig. 2, the two parts of the shot where they are in contact present a squared and equal surface against one another at exact right angles to the length of the shot, instead of any irregular contact

surface. This true bearing insures an equal impact from the force of the charge to the entire mass of the double shot, which gives the double shot an absolutely true direction 60 when it leaves the muzzle of the gun and does away with irregularity of flight which has been the defect of devices intended for the same purpose.

The section of the shot B is substantially 65 larger and heavier than the section C, as is shown by the drawing. This heavier section of the double shot insures a continuance of the true direction given by the initial impact. In other forms of chain shot, where 70 the sections have been of nearly equal or irregular shape, any accuracy of flight has been impossible. In my device the heavier section B (the head of the shot) maintains 75 its accuracy of direction and is not deflected by the smaller and lighter section C when this smaller and lighter section has separated from the section B. This separation is accomplished without any disturbance of the direction of the heavier section B because, as shown in Fig. 2, the contacting surfaces are flush so as to facilitate the separation of the shot members, without any joint or irregular surface. Any form of joint or 80 irregularity of surface, however slight, tends to deflect the direction of the shot when the sections of the shot separate. Whereas, in my invention, the sections of the shot separate with no friction or adhesion of any kind, and consequently no disturbance in 85 the direction of the shot.

The devices in various prior patents for chain shots, as known to applicant, differ from my invention in two important points which are the essentials of my invention.

90 First, the true bearing of one part of the shot against the other part of the shot at right angles to the length of the shot without joint or irregularity of any kind.

Second, the substantially heavier head of 100 the shot.

105 These two essentials insure, a true impact to the entire mass of the shot from the powder charge, a true direction of the shot on leaving the muzzle of the gun, and a continued true direction of the shot as a result of the heavier head of the shot retaining this true direction and dragging after it the lighter part of the shot. Forms of chain shot, such as the Ely and Gault U. S. Patents 34,626 and 34,628 do not show or describe these two essentials. The parts of

these old shots are joined by various devices, such as bands, screws and dovetail joints, and have no such true bearing to receive the impact of the charge and distribute it uniformly throughout the mass of the shot, and do not show or describe the heavier head necessary to insure the true flight of the shot.

In other forms of chain shot, various 10 irregularly shaped parts, balls, etc., separate themselves from the shot and there is nothing of the essentials above described. The lack of these essentials has made all such forms of shots useless on account of the 15 irregularity of their flight.

Various prior British patents, as known to applicant, such as the Storm and Goldstein patents, plainly show distinct differences from the applicant's device, in that in 20 each case there is a frictional joint holding the parts of the shot together, and this frictional joint prevents an equilibrium of separation, which is necessarily impossible from any fitting joint, and this inequality of separation is increased by the explosive charge, shown and described in each case as necessary to cause the separation of the two 25 parts of the shot.

In the Storm Patent 321 of 1861 the description of Fig. 9 states that "the powder inclosed in the shell will become ignited by the fuse, and exploding it will cause the separation of the coupled parts C and D."

In the Goldstein Patent 4393 of 1913 it 35 plainly states in claim 2 "wherein such exterior parts are held together by friction only until separated by the explosion of the internal charge."

In both British patents the drawings 40 clearly show frictional joints between the sections of the shot. On the contrary, in applicant's device, as is clearly shown in Fig. 2, the two parts of the shot are assembled with the abutting ends resting 45 against one another with squared and equal surfaces at right angles to the length of the shot with no frictional or other joint, so that the parts of the shot may separate with no friction or adhesion of any kind, and 50 consequently no disturbance of the direction of the shot. Moreover there is no use of explosives to cause the parts to separate, as in the two British patents.

In my invention there is no joint what- 55 ever between the parts of the shot. This makes it different from any form of chain shot known to me. I have been able to do away with the joining of the two parts because I have devised a way of holding the 60 two separate parts in assembled position preliminary to the discharge of the shot by use of

a cartridge case, as shown in Fig. 3. The shot is assembled as in Fig. 2, standing on its nose, with the parts adjusted to one another. Then the loaded cartridge case is slipped 65 down over the bearing between the two separate parts. In this way the closely fitting cartridge case holds the two separate parts in proper adjustment, and the two piece shot can be shipped, handled, and placed in the 70 gun with the two separate parts resting against one another as described above. Yet there is no joining of the parts, and the two separate parts are free to move away from 75 one another without friction or disturbance of any kind as soon as the shot leaves the muzzle of the gun in the discharge.

Having thus described the nature of my invention and set forth a construction embodying the same, what I claim as new and desire to secure by Letters Patent of the United States, is:

1. An improved chain shot consisting of two separate sections, one of which is heavier than the other, the separate sections in assembled position resting one against the other with squared and equal contacting surfaces at right angles to the length of the shot, each section free from any retaining device, and each section free to move away from the other section as the shot is discharged from the gun, and means for holding the two sections in their relative assembled position preliminary to the discharge of the shot from the gun. 90

2. An improved chain shot consisting of two separate sections, one of which is heavier than the other, the separate sections in assembled position resting one against the other with squared and equal contacting surfaces at right angles to the length of the shot, each section free from any retaining device, and means exterior to the shot for holding the two sections in their relative assembled position preliminary to the discharge of the shot from the gun. 95

3. An improved chain shot consisting of two separate sections, one of which is heavier than the other, the separate sections in assembled position resting one against the other with squared and equal contacting surfaces at right angles to the length of the shot, each section free from any retaining device, and a cartridge case for holding the two sections in their relative assembled position preliminary to the discharge of the shot from the gun. 100

In testimony whereof, I have signed my name to this specification, this fourteenth day of September, A. D. 1916.

THOMAS G. FROTHINGHAM.
